EXPLOSIVE ENGINE

Application filed December 5, 1928. Serial No. 323,960.

My invention relates to improvements in explosive engines. It is particularly adapted for use in two cycle engines.

One of the objects of my invention is to provide a novel two cycle explosive engine which eliminates crank case compression, and which effects compression of the explosive charges wholly within the power cylinder, which affords a maximum of compression, which effects a maximum discharge of exploded charges with a minimum of admixture therewith of unburnt charges, which reduces to a minimum resistance to the reciprocation of the piston, and loss of compression by leakage from the cylinder, which affords a short travel and direct admission of the explosive charges into the cylinder, and a minimum of space for compression of said charges, and which provides a simple structure, cheap to make, strong, durable and of great efficiency.

The novel features of my invention are hereinafter fully described and claimed.

In the accompanying drawing, which illustrates the preferred embodiment of my invention,

Fig. 1 is a vertical sectional view of my improved engine.

Fig. 2 is a similar view, partly broken away, showing the parts disposed in a position different from that shown in Fig. 1.

Similar reference characters designate similar parts in the different views.

1 designates the crank case having mounted therein the usual crank shaft 2, to which is connected the usual connecting rod 3. 4 designates the power cylinder the lower end of which rests on an annular flange 5 of an exteriorly cylindrical guide 6 having a vertical cylindrical bore and a closed upper end, the upper end and guiding walls being extended into and spaced from the cylinder side wall.

In the upper end of the cylinder 4 is mounted the usual spark plug 7. The cylinder 4 at one side near its middle is provided with an exhaust port 8. The other side of the cylinder 4 is provided with a by-pass 9, the upper end of which 10 is disposed just below the horizontal plane of the exhaust

port 8. The lower end 11 of the by-pass 9 is adjacent to and aligned with a charge inlet 12 which is controlled by a horizontally slideable valve 13 having a horizontal stem 14 which extends through and is slideable in the wall of a housing 15, which with the cylinder wall forms the by-pass 9, and which has a passage 16 through which the explosive charges are conducted to the by-pass 9.

A coil spring 17 encircling the stem 14 bears at one end against the housing 15 and at its other end against a washer 18 mounted on the stem 14. The spring 17 normally holds the valve 13 seated.

A piston has its head 19 reciprocatively mounted in the power cylinder 4, and the head is provided with a downwardly extending cylindrical skirt 20, which is provided with a lateral port 21 adapted, when the head is in the position shown in Fig. 1, to register with the lower end 11 of the by-pass 9, so as to permit a compressed charge under the head 19 to pass therefrom through the port 21 into the by-pass 9, and thence out the upper end 10 thereof into the cylinder above the head 19.

The skirt 20 is adapted to enter the annular space between the guide 6 and the side wall of the cylinder 4. The skirt 20 is adapted to close the exhaust port 8 and the ends 10 and 11 of the by-pass 9. The lateral port 21 is adapted with each stroke of the piston to consecutively register with the ends 10 and 11 of the by-pass 9.

The upper end of the head 19 is provided with the usual upstanding deflector projection 22, adapted, after the exhaust port 8 is uncovered on the down stroke of the piston, to be interposed between the discharge end 10 of the by-pass 9, and the port 8, so that the transferred explosive charge is deflected upwardly to the upper end of the cylinder 4.

The piston has a piston rod 23 rigidly fastened to the center of the head 19, and it extends downwardly vertically therefrom through the closed upper end of the guide 6 in which it is reciprocatively mounted. The lower end of the rod 23 is rigidly fastened to the center and upper end of a cylindrical cross head 24, which is reciprocatively snugly fitted

in the cylindrical bore of the guide 6. The cross head 24 has pivoted to it the upper end of the connecting rod 3, and it is provided with one or more longitudinal air passages 25, which on the downward stroke of the cross head prevents a vacuum being formed in the guide 6 above the cross head 24, while at the same time not interfering with the snug fitting of the cross head 24 in the bore of the guide 6. The movement of the cross head 24, also, is not resisted by compression of air in the guide above the cross head, so that the reciprocation of the cross head in the guide does not interfere with the free movement of the piston in the cylinder.

The closed end of the guide 6 is provided with piston rod packing means comprising a disk like packing collar 26 snugly but slidably fitted on the piston rod 23, and provided with internal annular grooves 27 for the reception of oil. The packing collar 26 is disposed in a cylindrical recess 28 in the upper side of the closed end of the guide 6, which recess has larger diameter and slightly greater depth, preferably, than the diameter and vertical thickness of the packing collar 26. A cover plate 29 is fastened, as by bolts 30 to the upper end of the guide 6, so as to close the recess 28. The cover plate 29 and the bottom of the recess 28 afford unyielding seats for the packing collar 26 to bear against.

The rod 23 extends through and is reciprocative in the cover plate 29.

The rod 23 on its upward movement carries with it oil from the crank case 1 into the recess 28 and into the annular grooves 27 of the packing collar 26. The latter is carried by the rod 23 against the under side of the cover plate 29, thus preventing air passing upwardly or compressed gas downwardly past the cover plate. On the downward movement of the piston rod 23, the latter carries the packing collar 26 against the bottom of the recess 28, and thus prevents leakage in either direction along the piston rod. This construction affords an oil packing for the rod 23 that permits no leakage of compressed gas into the crank case, nor of air from the crank case into the cylinder 4. The reciprocations of the piston rod are at such speed that the oil contained in the recess 28 is not given time to be forced therefrom, so that it makes a perfectly tight seal around the piston rod. By having the charge inlet 12 communicating with the by-pass 9, and by having the latter always in communication with the interior of the skirt, the charge is drawn into the cylinder during substantially the entire intake stroke of the piston head, thus affording maximum power and speed, and by having such large volume of fuel mixture drawn into the cylinder and compressed in the small space, due to the extension of the guide 6 into the skirt 20, a very high compression of the mixture is effected under the piston head, so

that the charge travels with great velocity and force through the by-pass into the combustion chamber, thereby exerting a maximum scavenging effect.

Such maximum scavenging of the combustion chamber by diminishing the dilution of the charge with exhaust products, effects a maximum of power and speed, and reduces the fouling of the combustion chamber with the products of combustion. As the packing collar 26 is of less diameter than the recess 28 and tightly seals around the piston rod 23 and the holes in the cover plate 29 and guide top 6, the piston rod need not be tightly fitted in said holes as the packing collar 26 is adapted for lateral play in the recess 28. This permits of less accuracy of alinement of the cross head and piston head, makes the machining of the parts easier and cheapens the cost of manufacture, as well as compensating for wear of the cross head and its guide, while retaining a tight sealing between the cylinder and the crank case.

In the operation of the engine, with the parts as shown in Fig. 2, and a charge which is compressed and above the head 19 having been ignited by the spark from the plug 7, the piston head 19 and rod and cross head move downwardly on the power stroke. Air will pass upwardly through the passage 25 in the cross head 24, thus avoiding the formation of a partial vacuum above the cross head in the guide 6. When the head 19 uncovers the port 8, the exhaust charge will pass outwardly through this port. On the downward movement of the piston, the head 19 will, after the head has uncovered the end 10, and the lateral port 21 of the skirt 20 registers with the other end 11 of the by-pass 9, cause the explosive charge, which has entered the cylinder 4 under the head on the upward movement of the piston, to be transferred from under the head 19, through the port 21 and by-pass 9 into the cylinder above the head 19.

Upon the upward movement of the piston, when the head 19 has passed the exhaust port 8, the explosive charge will be compressed, which is above the head 19, and a new explosive charge will enter the cylinder below the head 19 through the passage 16 in the housing 15, past the valve 13 and lower end 11 of the by-pass. Upon the next downward movement of the piston, the newly introduced charge will be transferred from below the piston head 19 through the by-pass 9 to the upper side of the head, in the manner already described.

By having the charge inlet 12 communicate with the by-pass 9 disposed in alinement with and adjacent to the end 11 of the by-pass, the charge after passing the valve 13 travels but a short distance and in a straight course. This enables the provision of a small compression space, so as to secure a maximum

of compression and dispenses with a separate intake opening in the side wall of the cylinder 4. By having the charge inlet 12 communicating with the by-pass 9, and by having the latter always in communication with the interior of the skirt, the charge is drawn into the cylinder during substantially the entire intake stroke of the piston head, thus affording maximum power and speed, and by having such large volume of fuel mixture drawn into the cylinder and compressed in the small space, due to the extension of the guide 6 into the skirt 20, a very high compression of the mixture is effected under the piston head, so that the charge travels with great velocity and force through the by-pass into the combustion chamber, thereby exerting a maximum scavenging effect.

Such maximum scavenging of the combustion chamber by diminishing the dilution of the charge with exhaust products, effects a maximum of power and speed, and reduces the fouling of the combustion chamber with the products of combustion.

With the employment of the outside bypass 9, the piston may be longitudinally imperforate, enabling the use of a solid piston rod and head, thus affording a maximum of strength and a very simple structure. By having the cylindrical cross head guide 6 have its guiding walls extending into the cylinder 4, a very small compression space is afforded, thereby greatly increasing the efficiency of the engine. It also affords the advantage of shortening the height of the engine, making it compact and less liable to lateral vibration than a taller engine.

I do not limit my invention to the structure shown and described, as many modifications, within the scope of the appended claims, may be made without departing from the spirit of my invention.

What I claim is:—

1. In an explosive engine, a cylinder having an explosion chamber provided with an exhaust port, a piston head reciprocative in said cylinder and arranged to close said port and having a skirt, a by-pass having a charge inlet and in constant communication with the interior of said skirt and adapted to communicate with said combustion chamber and disposed so as to be disconnected from said combustion chamber by said piston head, a cross head guide extending into and closing one end of said cylinder and, at the end of the power stroke of said piston head entering and being closely spaced from said skirt, a cross head reciprocative on said guide, a piston rod reciprocative through said guide and connecting said piston head and said cross head, and sealing means between said piston rod and said guide.

2. In an explosive engine, a cylinder having a closed end provided in its inner side with a recess, a cover plate fastened to said

end and closing said recess, said plate and the bottom of said recess forming unyielding seats, a piston head reciprocative in said cylinder, a piston rod fastened to said piston head and extending through and reciprocative in holes provided respectively in said cylinder end and in said plate, and a packing collar tightly and slidably fitted on said piston rod in said recess and reciprocative by said piston rod to positions in which it will alternately bear against the said seats respectively, said packing collar having less thickness and less diameter than the depth and diameter respectively of said recess, said packing collar having one or more internal annular peripheral oil receiving grooves.

3. In an explosive engine, a cylinder having a closed end comprising a cross head guide extending into said cylinder and having in its upper end a recess, a plate fastened to said guide and closing said recess, said plate and the bottom of said recess forming unyielding seats, a piston head reciprocative in said cylinder and having a skirt encircling and closely spaced from said guide when said piston head is at the end of its power stroke, a cross head reciprocative on said guide, a piston rod reciprocative through holes provided respectively in said guide and said plate, and a packing collar tightly and slidably fitted on said rod in said recess and reciprocative with said piston rod to positions in which it will alternately bear against said seats, said packing collar having less thickness and less diameter than the depth and diameter respectively of said recess, said packing collar having one or more internal annular peripheral oil receiving grooves.

In testimony whereof I have signed my name to this specification.

WENDELL R. MCKINNEY.
